Primary Examiner—Terry A. Wallace
Attorney, Agent, or Firm—Scott B. Garrison[57] **CLAIM**

I claim the ornamental design for a napkin dispenser cartridge, as shown and described.

DESCRIPTION

FIG. 1 is an oblique elevational view as seen from the left front edge of a napkin dispenser cartridge showing our new design;

FIG. 2 is a front elevational view thereof;

FIG. 3 is a left side elevational view thereof, the right side being a mirror image;

FIG. 4 is a rear elevational view thereof;

FIG. 5 is a top plan view thereof; and,

FIG. 6 is a bottom plan view thereof.
